(57) **CLAIM**

The ornamental design for an anchor for beach umbrella, as shown and described.

DESCRIPTION

FIG. 1 is a cross-sectional view of the anchor for beach umbrella in a first state of use;

FIG. 2 is a cross-sectional view of the anchor for beach umbrella in a second state of use;

FIG. 3 is a top view of the anchor for beach umbrella;

FIG. 4 is a bottom view of the anchor for beach umbrella; and,

FIG. 5 are the details of ribs support with collar and container cover in perspective.

In the drawings, the dashed lines depict environment and form no part of the claim. The dash-dot lines in FIG. 5 depict boundaries of the claim and from no part of the claim.
